GINGERBREAD COOKY

Harold Pollard, Sussex, N. J.

Application August 6, 1956, Serial No. 42,522

Term of patent 14 years

(Cl. D8—1)

Fig.1

The back of the cooky is conventionally plain and unornamented.

I claim:

The ornamental design for a gingerbread cooky, as shown and described.
